UNITED STATES PATENT OFFICE.

CLARENCE E. REED, OF HOUSTON, TEXAS, ASSIGNOR TO REED ROLLER BIT COMPANY, OF HOUSTON, TEXAS, A CORPORATION OF TEXAS.

ROTARY CORE DRILL.

Application filed December 18, 1922. Serial No. 607,720.

To all whom it may concern:

Be it known that I, CLARENCE E. REED, a citizen of the United States, and resident of Houston, in the county of Harris and State 5 of Texas, have invented certain new and useful Improvements in Rotary Core Drills, of which the following is a specification.

The invention consists in the features and combination and arrangement of parts here- 10 inafter described and particularly pointed out in the claims.

In the drawings Figure 1 shows the upper part of the apparatus partly in elevation and partly in central vertical section along the 15 plane of the port 14 in Fig. 2, but with the lower end in section on line 1-1 of Figure 4.

Figure 2 is a cross section on line 2-2 Figure 1.

Figure 3 is a sectional view on line 3-3 20 Figure 4.

Figure 4 is a bottom plan view.

Figure 5 is a part elevation and part sec- 25 tional view of the cutter head showing a cutter of the milling type and with a modified disposition of flushing fluid conduit.

Figure 6 is a vertical sectional view of another form of cutter head: at the right on line 6 and at the lower left on the line 6^a and the part above this is a section on the line 30 6^b of Figure 7.

Figure 7 is a bottom plan view of Figure 6.

In these drawings the drill stem section 1 is screwed into a coupling 3. The drill stem section 4 is screw threaded into the 35 lower part of this coupling. The drill head 6 is screw threaded onto the lower end of the drill section 4 at 5. This drill head carries lower cutters 7 and reamer cutters 8.

It has a central bore 9 which is closed by 40 a plug 10 having a fish tail or other bit 10^a at its lower end and an extension 11 which acts as a guide. This extension may be hollow. This plug is provided with screw threads at 12 which engage corresponding 45 screw threads in the bore of the cutter head. The cutter head has attached thereto by screw threads at 13 a core tube 15 which extends coaxially with the drill stem section 4 and at its upper end is fitted to the central 50 depending extension 2 of the upper plug 16. This extension has a central bore communicating with cross ports 14 which in turn connect with the exterior of the drill stem

through the hollow screws 18 by which the plug 16 is secured to the coupling 3. These 55 cross ports vent the interior of the core tube, the flushing fluid entering through the ports and filling up this tube. The plug 16 is of the form shown in Figure 2 providing passages 17 for the flushing fluid which passes down through the annular space 20 between the core tube 15 and the drill stem section 4, and thence by passages 19 Figure 3 in the drill head to points adjacent the cutters but 60 on the exterior of the drill head so as not to interfere with the formation of the core. The apparatus is also provided with valve members 21 hinged to pins 22 held by member 22^a in radial openings 23 of the drill head. The purpose of the plug 10 is to close 65 the core tube 15 and prevent it from receiving material at miscellaneous depths as the apparatus is being lowered to its work.

In the operation of the apparatus rotary 70 movement of the drill will cause the lower plug 10 to unscrew from its seat in the drill head and the material cut by the cutters 7 will pass to the center and force this plug up along the core tube and a central core of the material will thus be provided made up of 75 that which is actually cut, and excluding other matter, it being lodged in the core tube below the plug which will finally be arrested 80 by coming against the upper plug which closes the core tube. Hydraulic packing is 85 provided at 24. The hinged valves 21 will move inwardly and hold the core against falling down as the apparatus is withdrawn from the well. The venting of the interior 90 of the core tube will prevent too rapid upward movement of the plug, because this plug must, as it rises, expel this flushing water above it, from the tube.

The reamer cutters are held in pockets 25 of the drill head on journal pins 26. These 95 may be dropped into place as shown in Figure 6 and held by the coupling 27 bearing on their eccentric headed upper ends 28 which rest in sockets in the drill head. The cutters may be of various forms, besides those shown in Figure 1. Thus in Figure 5 the cutter 7^a is in the form of a milling cutter screw threaded onto the lower reduced end 29 of the cutter head, or as shown in Figure 6, the cutters may be of roller form 100 mounted as at 30 on inclined axes or as at 31

on horizontal axes or both forms may be used in the same head. The flushing water conduits are inclined as indicated at 19'.

- In Fig. 6 the rollers which cut the bottom 5 of the hole are illustrated as carried in the same, or one piece cutter head as the reaming cutters. In the commercial form the rollers which cut the bottom of the hole are preferably carried in a separate cutter head from 10 the body carrying reamer cutters. The cutter head and reamer body are joined by screw thread similar to the illustration in Fig. 5 in which the type of cutter 7^a is screw threaded to fit 29.
- 15 Where elements are susceptible of being embodied in one and the same form of the device it is to be regarded that they are to be embodied if desired. Thus the coupling 27 and head of Fig. 6 might be used in the 20 place of the cutter head of Fig. 1, or the cutters of Figs. 5, 6 and 7 may be used in Fig. 1. The apparatus is used in connection with deep well drilling operations to secure

from the bottom of the well cores of material by which character of the strata may be as- 25 certained.

I claim:

1. In apparatus of the class described, the combination of a drill stem, a core tube therein, a drill head having cutters, members for locking the core in the core tube, and pins to which said members are pivoted held in radial sockets or openings of the drill head, substantially as described.

2. In combination a drill head, a drill stem 35 in sections, a coupling between the sections, a plug having a central bore and a cross bore, hollow screws for holding the plug to the coupling, and in connection with the cross bore venting the interior of the plug, and a 40 core tube connected with the plug and with its bore communicating with the bore of the plug, substantially as described.

In testimony whereof, I affix my signature.

CLARENCE E. REED.
